REVERSIBLE DRIVE FOR FEED MECHANISM

Fill C. Sanders and Aberhart P. Kling,
Vimy Ridge, Ark.

Application December 21, 1948, Serial No. 66,498

3 Claims. (Cl. 74—218)

1

This invention relates to drive means for conveyors and feeding devices associated with sawmills and the like, and particularly to a reversible drive or feed mechanism therefor.

The main object of our invention is to provide manually-controlled drive means for operating a feed or conveyor carriage mechanism a limited distance in one direction and then reversing the operation a corresponding distance in the opposite direction, and so indefinitely.

Another object is to provide a sawmill or other apparatus with a reversible drive which is readily controlled and reversed at will by means of a single manually-operated lever in connection with which the direction of a drive is determined by the direction of movement of the lever.

A further object is to have a reversible drive of the character indicated in which a pair of shafts which are each provided with a pair of power transmission means capable of being alternatively connected with one of the corresponding transmission means on the other shaft for driving in either selected direction of two possible opposite directions of rotation at will.

An ancillary object is to have a pair of pulleys secured on a drive shaft with a pulley and a friction-engaging member secured on another shaft which is mounted in such fashion as to be shiftable toward or from the first-mentioned drive shaft for selecting the direction of operation to be transmitted from said drive shaft to the other shaft.

It is also an object to have a reversible drive mechanism of the mentioned type which is simple in construction and not only effective and certain to operate in use, but which requires only a trifling movement for transmitting power from one shaft to the other in the selected direction of operation, and also includes an intermediate neutral or inactive condition of adjustment.

Other objects and advantages of our invention will appear in further detail as the specification proceeds.

In order to facilitate ready comprehension of this invention for a proper appreciation of the salient features thereof, the invention is illustrated on the accompanying drawings forming part hereof, and in which:

Figure 1 is a fragmentary plan view of a sawmill equipped with a reversible drive or feed mechanism made according to the invention and embodying the same in a practical form, a limited portion of the conveyor being included, while the saw table is omitted for clarity in the view;

Figure 2 is an enlarged side elevation of the

2

reversible drive or feed mechanism of the invention, with portions of the apparatus of Figure 1 omitted to facilitate illustration of the main features of the invention;

5 Figure 3 is a plan view of the portions of the invention illustrated in Figure 2, parts being broken away and parts also being shown in section;

Figure 4 is a fragmentary section on an enlarged scale of a chain drive portion of the apparatus of Figure 1;

10 Figure 5 is an end elevational view taken on the line 5—5 of Figure 1;

15 Figure 6 is a plan view of a saw cut guide or split knife of Figure 1 shown on an enlarged scale;

Figure 7 is an elevation of the same saw cut guide or split knife as seen from the bottom in Figure 6;

20 Figure 8 is a perspective view of the same saw cut guide or split knife of Figures 6 and 7.

Throughout the views the same reference numerals indicate the same or like parts.

In connection with various kinds of machinery, 25 and especially on sawmills, it is desirable to have means for feeding and conveying pieces of wood and heavy lumber upon the mill to the saw to be cut into lumber, and also for reversing the feed conveyor or carriage in order to bring the same back to a starting position again. It is self-evident that means for thus operating the carriage in one direction and then reversing movement thereof must be of such nature as to be primarily simple and then also unobtrusive and 30 likewise easy to operate and control.

Upon considering this problem, it has occurred to us that a reversible drive could well be built into the framework of a sawmill and operated from the mandrel of the circular saw in such 35 fashion as to be alternatively engageable with one or the other of a pair of different transmission members on the mentioned mandrel by means of a simple manually-operated lever so that one direction of movement of the lever would cause feeding of the carriage or feed mechanism in one direction and adjustment of the lever in the opposite direction would cause reverse or return operation of the feeding mechanism or carriage. As a result, we have found it quite feasible 40 to produce a reversible drive or feed mechanism for such a machine as will now be more fully described.

Hence, in the practice of our invention, and referring again to the drawings, a sawmill frame 45 primarily includes a plurality of cross-beams

50 55 9

or frame members 10 (one shown), and a plurality of longitudinal frame members 11, 12 and 13 secured to the transverse members 10, etc., and upon the longitudinal frame members 11 and 13 are secured a pair of aligned bearings 14 and 15 for rotatably carrying a saw mandrel or shaft 16 upon one end of which is fixed a circular saw 17 by means of a pair of flanges 18 and 19 disposed between two nuts 20 and 21 screwed upon the threaded end 22 of shaft 16. Upon the other end of the mentioned shaft is fixed a large pulley 23 to which a drive belt 24 is connected and driven by a prime mover (not shown), while in association with the frame, generally indicated at 9, is provided movable feeding means, to be described, and serving as a saw table or carriage upon which planks, boards, lumber and various pieces of wood may be fed forwardly from the direction of cross-piece 10 toward the saw blade 17, while a more or less conventional rip fence and guide means or supports may be used on the carriage, these latter parts being omitted to clarify the view, inasmuch as they are so well known as to be understood upon mere mention thereof.

Thus far described, the sawmill is more or less conventional, but in connection with the same the feeding means referred to, generally indicated at 25, primarily includes a movable carriage 26 which is located adjacent the frame 9 at a level which allows lumber lying thereon to be sawed by circular saw 17 while being fed past the latter on the carriage.

During the sawing operation, a special saw cut guide or split knife 27 serves to prevent binding or warping of the wood in such manner as to clamp the saw blade and slow down rotation thereof, this split knife 27 primarily consisting of a base portion 28 having a pair of slots 29 through which a pair of adjusting bolts 30 extend down through, or at least into, the frame member 13 and a block 31 secured to the frame member in such fashion that the base 28 may be adjusted along the slots 29 upon partial releasing of the bolts 30. The mentioned split knife 27 includes a slot or cut retainer 32 extending vertically in substantially the same plane as the saw blade 17 and being of the same width therewith for the purpose of entering into the saw cut produced by saw blade 17, thereby preventing collapse of the wood and clamping of the saw disc. Such occurrences may in some cases be exceedingly dangerous, as the saw may suddenly seize the wood and project it violently rearward toward the operator. The mentioned split knife forms a slot retainer 32 which is virtually a blade having an arcuate entering edge 33 which is sharpened to be at least wedge shape to facilitate the work sliding past the same on both sides, it being obvious that several such guide members 27 may be used, each one having its upwardly-projecting split knife 32 of the proper thickness to correspond to the width of the saw blade being used.

Further, beneath feeding carriage 26 are located a pair of guide rails 34 and 35 for guiding and supporting the same beyond the frame member 13, as will presently appear.

In order to operate the conveyor mechanism and thus feed and return carriage 26 along rails 34 and 35, power is taken from the saw mandrel or shaft 16 in a manner which particularly includes the features of this invention. Upon the shaft 16 are mounted a pair of pulleys 37 and 38, the pulley 37 being of considerably smaller diameter than that of pulley 38, while in line with the mentioned smaller pulley is a relatively larger pulley 39 fixed upon the shaft 40 rotatably upon a longitudinal rod 48 fixed upon a pair of brackets 49 and 50 at the ends thereof, these brackets being mounted upon the longitudinal frame member 11 transversely of the axes of shafts 16 and 40. On the guide rod 48 are fixed a pair of stop collars 51 and 52, while upon the same rod are mounted a pair of compression springs 53 and 54 between the collars 51 and 52 and the slidable blocks 46 and 47 to which bearing 45 is secured by the screws or bolts 55, 55. If desired, both slidable blocks 46 and 47 and bearing 45 may be formed into a rigid unit and slidable as such on rod 48.

On the shaft 40 in substantially the same plane with pulley 38 on shaft 16 is fixed a wheel, generally indicated at 36, forming a transmission member with a resilient rubber or plastic tire 56 normally spaced but a very short distance from the surface of pulley 38. At the same time, pulleys 37 and 39 are interconnected by means of a flat belt 57 which is normally tight in such fashion as to transmit rotation from pulley 37 to pulley 39 when tire 56 is out of contact with pulley 38. To the ensemble including members 46 and 47, as well as the bearing 45 between the two and secured to the same, is connected a link 58 by means of a pin or screw 59 at the inner end of link 58, while at the outer end this link is provided with a fork 60 connected by a pin 61 to the outer end of an arm 62 mounted on a lever control shaft 63 supported in bearings 64, 65 secured upon members 11 and 13 of frame 9 by means of screws or bolts 66. Upon the same lever control shaft 63 carrying arm 62 is fixed a manually-operated lever 67 of sufficient length to provide effective purchase to partially rotate shaft 63 by means of lever 67 when the same is either pulled or pushed by hand. The arrangement is such that when the lever is extended outward, as shown at 67 in Figure 1, link 58 exerts a sufficient pull upon bearing 45 to draw pulley 39 away from pulley 37 and tighten belt 57, causing rotation of circular saw mandrel or shaft 16 to be transmitted through belt 57 to pulley 39 on shaft 40. When the lever 67 is manually pushed inward or toward the left in Figure 1, link 58 will exert a push upon bearing 45 toward shaft or mandrel 16 against spring 53 and will slack belt 57 so that rotation of pulley 37 will no longer be transmitted to pulley 39, but instead tire 56 will be in direct frictional contact with the periphery of pulley 38 and thus shaft 40 will be rotated in the opposite direction to that which previously was transmitted thereto through belt 57. The shifting of bearing 45 is facilitated by the swivel or pivotal mounting 42 of bearing 41 on bearing base 43 supported on longitudinal frame member 12.

Returning now to a detailed consideration of the feed mechanism, the carriage 26 is provided therebeneath with a pair of wheel axles 74, 74 mounted for rotation in bearings 75, 75 secured to the under side of the carriage and provided upon the ends thereof with supporting wheels 76, 76 riding on rails 34 and 35. The rails are se-

cured upon a pair of longitudinally-arranged rail base members 11, 18 between which are secured a pair of brace bars 79, 80, while to rail base member 11 are attached a pair of brackets 81, 81 by means of bolts 82, 82. These brackets are secured also to the outer sides of frame member 13 by bolts 83, 83, thus rigidly connecting the rail structure with frame 9.

The purpose of the previously-mentioned reversal of shaft 40 which may be effected during rotation of shaft 16 by means of the control lever serves in this case to provide limited movement of feed carriage 26 in the forward direction and then an equal movement in the opposite direction on rails 34, 35 following such forward movement. Thus, upon the inner end of shaft 40 is fixed a sprocket 68 connected by a chain 69 to a relatively larger sprocket 70 fixed upon a shaft 71. This shaft is rotatably supported in a pair of bearings 72, 73 supported beneath frame members 12 and 13, while upon the far end of shaft 71 beneath carriage rail base members 11, 18 a drum 84 is secured thereto. Upon the under side of carriage 26 are fixed a pair of eyes 85, 86 to which the ends 87 and 88 of a cable, generally indicated at 89, are anchored, the cable ends being doubled back over a pair of sheaves 90, 91 in bearings 92, 93 beneath braces 79, 80 and then brought to the opposite ends of drum 84. Upon the latter drum the main bulk of the cable is of a length to provide a series of turns 94 wound thereon in such fashion that rotation of the drum in one direction will cause carriage 26 to travel with the cable in that direction, while when rotated in the opposite direction, the drum 84 will cause the cable 89 to feed carriage 26 in the opposite direction.

Thus, rotation imparted by shaft 16 to shaft 40 in one direction will cause shaft 71 and drum 84 mounted thereon to rotate in the same direction as saw mandrel 16 when belt 57 is tightened by a pull on lever 67. When the lever is pushed toward the left in Figure 1, belt 57 is slack and instead the tire 56 on wheel 36 will engage frictionally with pulley 38 and shaft 40 will be rotated in the opposite direction which will also be true of shaft 71 and drum 74, with the result that carriage 26 will be propelled in the opposite direction to that in which it previously was shifted, and thus the carriage may be fed forwardly in the direction of travel intended for the wood to be sawed by circular saw 17, and may thereafter be returned to original position to receive more lumber thereon for further feeding and sawing thereof in the original direction merely by controlling handle or lever 67.

In view of the fact that the saw shaft or mandrel 16 carries a heavy load both in sawing and in driving, in the reversible drive mechanism described, the bearings 14 and 15 thereof are preferably secured by bolts 95, 95 to pillow blocks 96, 97, which in turn are secured to frame members 11 and 13 by bolts 98, 98 providing a rigid and firm support for the bearings and the shaft involved.

It is to be noted that pulleys 39 and 37 bear the same relation to each other as the tire-equipped wheel 36 outside tire 56 to pulley 38, so that in either direction of rotation, shaft 40 runs at substantially the same speed. Should it be desired to make the carriage feed member 26 travel more swiftly on the return movement than during forward feeding movement, it is but necessary to increase the size of pulley 38 with respect to the tire 56 on wheel 36 in contrast with

5 pulley 39 in its proportional size and diameter to pulley 37.

While we have described the reversible drive mechanism as operating a feed carriage associated with a sawmill, it is understood that this is simply a non-limiting example of its use, and hence, the apparatus of the invention may be applied to, or built into, any machine or apparatus desired in which it may serve to provide operation reversibly under manual control.

Manifestly, variations may be resorted to and parts and features may be modified or used without others within the scope of the appended claims.

Having now fully described our invention, we claim:

1. Reversible drive mechanism, including a pair of fixed bearings, a drive shaft rotatably mounted in the fixed bearings, pulley means fixed on the drive shaft, there being means for driving said shaft in one direction, a second pair of bearings, means for shiftably supporting at least one of the latter bearings, a driven shaft rotatably mounted in said second pair of bearings and having a power take-off adjacent to the other of said second pair of bearings, a pulley fixed on the driven shaft adjacent to the one shiftably-supported bearing, a belt connecting the latter pulley with a portion of the pulley means on the drive shaft, a resilient tire-equipped wheel also mounted on said driven shaft close to, but normally out of contact with, another portion of said pulley means on said drive shaft, and manually-controlled means for shifting said one shiftable bearing and thereby shifting one portion of said driven shaft toward or from said pulley means in order to bring said resilient tire-equipped wheel selectively into driving contact with the other portion of said pulley means and to separate the last-mentioned parts and tighten said belt at will.

2. Reversible drive mechanism, including a pair of fixed bearings, a drive shaft rotatably mounted in the fixed bearings, pulley means fixed on the drive shaft having driving contact portions thereon, there being means for driving said shaft in one direction, a second pair of bearings, a shiftable support for one of said second pair of bearings, a driven shaft rotatably mounted in said second pair of bearings and having a power take-off adjacent to the other of said latter bearings, a pulley fixed on the driven shaft adjacent to the one shiftably-supported bearing, a belt connecting the latter pulley with a driving contact portion of the pulley means on the drive shaft, a resilient tire-equipped wheel also mounted on said driven shaft close to, but normally out of contact with, another driving contact portion of said pulley means on said drive shaft, a manually-operated lever pivotally mounted at one end thereof in spaced relation to the shiftably-supported bearing, an operating arm rigid with said manually-operated lever having one end thereof projecting into operative position, a link connecting said projecting portion of said arm with the shiftably-supported bearing in effective position to allow said arm upon movement of said lever to shift said shiftable bearing toward or from the drive shaft and thereby shift one portion of the driven shaft and the pulley and tire-equipped wheel thereon in order to selectively tighten said belt or to slack said belt and instead bring said tire-equipped wheel into contact with the other driving contact portion upon said pulley means at will.

3. A reversible drive means including a supporting frame, a pair of fixed bearings mounted upon said frame, a drive shaft rotatably mounted in said fixed bearings, a pair of pulleys fixed upon said drive shaft, there being means for driving said shaft in one direction, an elongated guide member fixed upon said frame, bearing support means slidably mounted upon said guide member, resilient means mounted upon said guide member in effective position to resiliently dampen movements of said bearing-support means in either direction along said guide member, a bearing fixed upon said bearing-support means, a further bearing aligned with said last-mentioned bearing mounted upon said frame, a driven shaft rotatably mounted in said last-mentioned two bearings, a pulley fixed upon said driven shaft substantially in line with one of the pulleys on the drive shaft, a resilient tire-equipped wheel also fixed upon said driven shaft in line with the other of the two pulleys on said drive shaft, a belt connecting the pulley on said driven shaft with the first-mentioned pulley on said drive shaft, a third manual control shaft mounted upon

said frame, a manually-operated lever fixed upon the third shaft, an operating arm also fixed upon said third shaft, a link interconnecting said arm and said bearing-support means for shifting the latter along said guide member upon movement of said manually-operated lever in order to selectively tighten said belt or bring said tire-equipped wheel into driving contact with said other pulley on said drive shaft, at will, and a power take-off on said driven shaft adjacent to the second bearing supporting said driven shaft.
